UNITED STATES PATENT OFFICE.

JULIUS H. COOPER, OF ROCHESTER, NEW YORK.

CARBURETER.

941,406.

Specification of Letters Patent. Patented Nov. 30, 1909.

Application filed March 27, 1908. Serial No. 423,697.

To all whom it may concern:

Be it known that I, JULIUS H. COOPER, a citizen of the United States, residing at Rochester, in the county of Monroe and State of New York, have invented certain new and useful Improvements in Carbureters, of which the following is a specification.

This invention relates to carbureters, and more particularly to convertible mechanically or automatically governed carbureters, and has for its object to provide such a device which may be used for volatilizing oils of various kinds.

Another object is to provide a carbureter by the use of which both the supply of oil and of air may be heated.

Another object is to provide a carbureter arranged to admit oil and air in regulated proportions and variable quantities.

Another object is to provide a means for diffusing the oil over a large heated surface to facilitate volatilization thereof.

Another object is to provide a means for directing incoming air forcibly against the supply of oil.

Another object is to provide a novel means for heating the supply of oil and air coincidentally with their being brought into mutual contact.

Another object is to provide a novel and desirable throttling means.

Another object is to provide a novel and desirable automatic governing means.

Another object is to provide a carbureter of this type in which the use of a float feed fuel governor may be dispensed with.

Another object is to provide such an article of simple structure which may be easily taken apart.

Another object is to provide a carbureter having an adjusting means of extreme simplicity.

Another object is to provide such an article which may be manufactured at low cost.

Other objects and advantages will be apparent from the following description, and it will be understood that changes in the specific structure shown and described may be made within the scope of the claims, and that any suitable materials may be used without departing from the spirit of the invention.

In the drawings forming a portion of this specification, and in which like characters of reference indicate similar parts in the sev-

eral views, Figure 1 is a top plan view of the carbureter, Fig. 2 is a side view of the carbureter, Fig. 3 is a cross sectional view laterally of Fig. 2, through the center of the mixing chamber, Fig. 4 is a bottom view of the carbureter, Fig. 5 is a horizontal sectional view on the line 5—5 of Fig. 3, Fig. 6 is a detail of the mixture controlling means, Fig. 7 is a similar view at right angles to Fig. 6.

Referring to the drawings, there is shown a carbureter comprising a chamber A to which there is secured a throttle section B. The chamber A comprises a cylindrical chamber having a wall portion 10 the lower outer end portion being threaded as at 11, and having a base portion 13 engaged thereon, as shown. The base portion comprises a floor portion 14 having an upwardly extending flange 15 therearound threaded on its inner face and engaged on the threaded portion 11 of the wall 10. A cone shaped projection 16 is located concentrically of the floor 14, its base being spaced inwardly from the wall 10. A fuel tube 17 extends upwardly concentrically through the floor portion 14 and communicates with an opening 18 at the apex of the cone 16, the lower end of the tube 17 projecting outwardly from the floor 14 and being threaded for engagement with fuel supply connections in the usual manner. The junction of the cone 16 with the floor 14 forms a chamber 20 as shown. Two openings 21 are formed in the floor 14 inwardly of the base of the cone 16 communicating with the chamber 20, and have interiorly threaded bosses 22 outwardly thereof arranged for connection with a heating means of suitable type.

A series of perforations 23 are formed concentrically of the base 14 between the base of the cone 16 and the wall 10 for the passage of air inwardly therethrough. The walls 10 are turned inwardly at their upper end, and form a support portion 25 having a circular opening 26 therethrough arranged to receive a valve controlling mechanism subsequently to be described. A skeleton piston 30 is located within the chamber and comprises a conical portion arranged to engage over the cone 16, having a vertical flange 31 extending upwardly from its base for close sliding engagement against the wall 10, and having its upper end open and flared outwardly as shown at 32. An ear 33 is carried adjacent to the upper edge of

the flared portion 32, provided with an opening 34 arranged for pivotal connection with the valve operating mechanism C subsequently to be described.

5 The valve operating mechanism C is disposed within the opening 26 and comprises a retaining member 35 formed in the shape of a short cylinder disposed revolvably in the opening 26 and having a laterally extending flange 37 secured upon the portion 26 by means of screws 38. A pendent fulcrum arm 40 is carried by the retaining member 35 extending longitudinally below the cylinder 36 and in spaced relation therewith. An oblong opening 41 is formed at the base of the arm 40 and has slidably engaged therein a threaded pin 42 carried pivotally at one end of a horizontal lever 43 extending beneath and adjacent to the axis 10 of the cylinder 35 the lever 43 being provided with an oblong slot extending longitudinally thereof and disposed adjacent to the axis of the cylinder 35. A nut 42' is engaged on the outer end of the pin 42 to 15 secure it adjustably therein. A connecting rod 45 is pivoted to the opposite end of the lever 43 and to the ear 44 for sliding operation of the piston 30 when the lever 43 is oscillated. A revoluble bushing 48 is engaged within the cylinder 35, having a flange at its lower end engaging against the base of the cylinder 35 and provided with an inwardly projecting portion 49 at its upper end. The opening 50 through the 20 upper end of the bushing 48 is threaded and has engaged therein a screw 51 extending through a retaining washer 51' disposed over the bushing 48. An inclined slot 52 having a vertical extension at its lower end 25 is formed in the side of the bushing 48 and has slidably engaged therein a pin 53 carried by a needle member 54 engaged slidably in the bushing 48. The needle member 54 extends downwardly through the chamber A, the lower end of the needle being pointed and seated in the opening 18 at the apex of the cone 16. A helical spring 55 is engaged between the portion 49 of the bushing 48 and the top of the needle 54, to 30 hold the needle at the lower limit of its movement. A pin 56 extends laterally from the needle 54 adjacent to the lever 43, and is engaged in the opening 44 to cause oscillation of the lever 43 when the needle is moved vertically. An operating lever 57 is secured to the bushing 48 above the cylinder 36, and is held adjustably thereon by means of a set screw 58.

It will be seen that upon operation of the 60 lever 57 the bushing 48 will be rotated, and the slot 52 will engage against the pin 53 to move the needle 54 vertically, the pin 56 at the same time engaging with the lever 43. It will thus be seen that the skeleton piston 65 30 will be raised from engagement against

the cone 16 at the same time that the point of the needle 54 is raised in the opening 18. The ratio between the movement of the piston 30 and the needle 54 may be governed by means of the adjustment of the pivot pin 42 in the slot 41 of the arm 40.

A circular outlet opening 60 is formed in the upper portion of the wall 10, being provided with a valve seat 61 at its outer end and having a circular boss 62 extending therearound to support a throttle mechanism to be described. A deflector flange 62' is carried by the walls 10 adjacent to and laterally of the opening 60 extending diagonally upwardly and inwardly thereof for a purpose to be subsequently indicated. A stem bearing arm 64 extends inwardly across the opening 60, and is provided with a bearing opening therethrough having a stem 65 slidably engaged therein carrying a valve 66 arranged for engagement with the seat 61. The stem 65 extends through the valve 66 and is engaged through an opening 67 in a bridge piece 68 extending across the interior of a valve casting 69 secured to the boss 62. The valve casting 69 comprises a casting of cylindrical shape having a flange 70 provided with a series of perforations 73 corresponding with a similar series 73' formed in the boss 62, and having screws 74 engaged therethrough to hold the casting in engagement with the valve chamber A, the outer extremity of the casting 69 is threaded for engagement with supply pipes. An L extension is formed on the casting 69 of similar size to the outer end of the casting and being similarly threaded. A boss 75 is formed upon the upper portion of the casting 69 and is provided with an opening 76 communicating with the interior of the casting having a shaft 77 revolvably engaged therein, the upper end of the shaft being provided with a lateral enlargement 78 outwardly of the boss 75 and carrying at its base a cam member 79 arranged to bear against the outer side of the valve 66. A threaded recess is formed in the upper end of the shaft 77. It will be seen that a throttle lever may be secured upon the portion 78 and retained in engagement thereon by means of a screw engaged in the recess 79'. Upon oscillation of which lever the cam 79 will be rotated to restrict or increase the limit of movement of the valve 66.

It will be seen that the present carburetor 120 may be connected with inlet of a gasoline motor, and used either as a mechanically governed mixer or as an automatically governed one. By means of the lever 57 it will be seen that the proportion of air to the fuel entering the chamber may be regulated to any desired extent as above described. The supply of fuel will be diffused over the surface of the cone 16, and thus offer the greatest area for evaporation through the contact 130

of the incoming air, the piston 30 serving to direct the air against the fuel spread on the cone, and also to promote contact with the greatest possible quantity against the fuel supply. The deflector 62' will serve to prevent unevaporated fuel from passing directly to the outlet opening 60 from the cone 16 and also thoroughly mix the vapor.

If it is desired to use the carbureter as an automatically governed mixer, the lever 57 may be oscillated beyond the normal limit of its movement to bring the vertical portion of the slot 36 over the pin 53 in the needle 54. The force of incoming air will thus raise the piston 30 and operate the needle 54 relatively to supply a quantity of fuel proportionate to the amount of air passing through the carbureter.

It will also be apparent that by making proper connections between the openings 21 and the heating means both the supply of air and the supply of fuel may be heated. It will be understood that suitable check means may be provided to limit the movement of the lever 57.

What is claimed is:—

1. A carbureter of the class described comprising a wall portion forming a mixing chamber, said chamber having an outlet, a conical base carried by the wall portion, a fuel passage communicating with said chamber through the apex of said conical base, said base having a peripheral series of air inlets therethrough, a piston engaged slidably in the chamber, and having a conical recess in its base arranged to engage closely with said conical base, said piston being arranged to close said air inlets when so engaged, said piston having an upwardly flared opening concentrically therethrough, a needle valve seated upon the apex of said base, means for operating said valve to admit fuel to the chamber, operative connections between said piston and the needle to raise the piston for the admission of air in fixed ratio with respect to the quantity of fuel entering the chamber, and means for adjusting the connections between the needle and piston to vary the said ratio.
2. A carbureter of the class described comprising a wall portion forming a mixing chamber, said chamber having an outlet opening through said wall, a base carried thereby having a conical extension projecting into the said chamber, said base having a series of air openings peripherally of said conical extension, a piston engaged slidably within the chamber and having a conical recess therein arranged to engage over said conical extension of the base, said piston

having an opening concentrically thereof to allow passage of air therethrough when in raised position, a valve engaged over the opening of said fuel passage, means for operating said valve and said piston simultaneously to admit air and fuel in fixed ratio to said chamber, and means for adjusting said ratio between air and fuel entering the chamber.

3. In a carbureter having a mixing chamber, the combination with a conical floor having a concentric peripheral air inlet, and a central reduced fuel inlet at the apex of the floor, of a piston valve comprising an annular member having a conical recess therein adapted to engage closely over the conical floor, and having an enlarged outwardly flared opening extending upwardly therethrough, a vertical needle valve seated in the opening through the conical floor, and adjustable connections between the needle valve and the piston for coöperation to admit air and fuel in a predetermined ratio.

4. A carbureter having a needle valve, a separate slideable air valve, adjustable connections coengaged with the air valve and needle valve to regulate the relative movement of the two valves, a mechanical means for operating the valves, said means comprising a sleeve revolvably engaged around said needle valve and having a peripheral slot therein extending diagonally with relation to the axis of the sleeve and having a longitudinal extension at one end, a lateral pin carried by the needle and engaged slidably in the slot, for longitudinal movement of the needle upon rotation of said sleeve, means for rotating the sleeve, and a spring engaged outwardly of the needle valve to yieldably resist operation thereof, said needle valve being adapted to be automatically governed by the movement of the air valve when the sleeve is rotated to bring the pin into alignment with the longitudinal extension of the slot.

5. A carbureter including an air inlet valve, a fuel valve, each of said valves being slideable, a lever pivoted variably adjacent to one of said valves, said lever being variably engaged with said last named valve intermediate of its length, and a link connection between the outer end of said lever and the other valve.

In testimony whereof I affix my signature, in presence of two witnesses.

JULIUS H. COOPER.
